UNITED STATES PATENT OFFICE.

JOHN VON FRIELING AND HENRY VON FRIELING, OF GAYLORD, KANSAS.

AUTOMATIC DOOR-LOCKING DEVICE.

1,221,635.

Specification of Letters Patent.

Patented Apr. 3, 1917.

Application filed October 31, 1916. Serial No. 128,792.

To all whom it may concern:

Be it known that we, JOHN VON FRIELING and HENRY VON FRIELING, citizens of the United States, residing at Gaylord, in the county of Smith and State of Kansas, have invented new and useful Improvements in Automatic Door-Locking Devices, of which the following is a specification.

This invention relates to automatic locks, 10 and is especially adapted for use in connection with the doors of toilet rooms upon railway or other cars.

The object of the present invention is to provide an automatic means for locking the 15 door of the toilet room of a railway or other car, as it approaches the town.

Another object is to provide an automatic means for unlocking the said door just after the car leaves the town.

With these and other objects in view the 20 invention consists of a spring pressed rack bar, mounted beneath the car, a ramp located in the path of the rack bar, gears operated by the said bar and provided with 25 ratchets to allow them to turn only in one direction, a pitman operated by the said gears and a pivoted bar connected to the pitman for operating the lock of a bolt within the car.

30 In the drawings:—

Figure 1 is a longitudinal sectional view of a portion of a railway car having the 35 invention applied thereto, the ramp for operating the invention being shown in a position about to engage the spring pressed bar;

Fig. 2 is a horizontal sectional view of the 40 mechanism located beneath the car, this section being taken on the line 2—2 of Fig. 1;

Fig. 3 is a detailed view of the ratchet mechanism;

Fig. 4 is a detailed sectional view through 45 the ratchet mechanism on the line 4—4 of Fig. 1;

Fig. 5 is a diagram illustrating the position of the pivoted lever and the bolt when the door is locked;

Fig. 6 is a similar view with the door unlocked.

50 In the operation of railway coaches it is very desirable that the doors of the lavatories be securely locked when passing through a town, and that they be unlocked after the town is passed. This duty falls to the members of the train crew, and is

sometimes forgotten or neglected, which causes annoyance either to the passengers, or to the railway officials. It is to overcome these disadvantages that we have provided the following described invention.

60

In the practical construction of the invention there is provided beneath the car 1 a suitable supporting arm, comprising a substantially semi-circular member 2, and a cross bar 3. This arm is provided with a sliding bearing 4 in which operates a rack bar 5. An arm 6 secured to the truck 7 of the car is provided upon its outer end with a bearing 8 through which the bar 5 is also adapted to operate. Interposed between the 70 bearings 4 and 8 is a coil spring 9 the action of which is to force the bar 5 downwardly, a suitable stop or collar 10 being provided upon the bar to limit its downward movement. Upon the lower end of 75 the bar 5 is a roller 11, and secured to the ties of the track in the path of this roller, is a ramp 12.

65

Upon the opposite end the bar 5 is provided with rack teeth 13, adapted to engage 80 the teeth of the pinion 14, mounted upon the axle 15 in bearings provided in the bar 3. Loosely mounted upon the shaft 15 is a gear wheel 16, which is adapted to be locked to the said shaft through the medium of 85 suitable ratchet mechanism. This mechanism consists of a disk 17 fixed upon the shaft 15, and having pivoted thereon as at 18 a number of pawls 19. Springs 20 urge these pawls into engagement with ratchet 90 teeth 21 formed upon the interior of the gear wheel 16.

95

Mesling with the wheel 16 is a gear wheel 22, having its shaft 23 journaled in bearings in the bar 3. Upon the shaft 23 is 95 mounted a disk 24 having pivoted thereon a pitman 25. A pivoted lever 26 is connected to this pitman, and has its opposite end connected to a suitable pulley 27, for locking the door of the lavatory shown at 28.

100

In the operation of the invention as above described the roller of the rack bar 5 is adapted to be raised against the action of the spring, by the ramp 12, which is located just in advance of the town. The raising of the bar 5 causes the wheel 14 to be rotated one half of its circumference, there being just enough teeth in the rack bar to cause this rotation. This causes the disk 24 to revolve one half way around 110

through the medium of the gears 16 and 22, the said disk operating the pitman and rocking the pivoted lever 26 to release the bolt 27 as shown in Fig. 5. After the roller 11 has passed over the ramp the rack bar 5 is returned to its original position through the action of the spring 9, the ratchet mechanism permitting of its return without disturbing the gears 16 and 22. After the train 10 has left the town the bar 5 will again cause the rotation of the pinion 14 by its engagement with another ramp, this action causing the movement of the gears 16 and 22, and the pitman 25, which moves the pivoted lever 26 in a direction to withdraw the bolt 27 and unlock the door.

Having described our invention what we claim is:—

1. An automatic locking device comprising a plurality of gears, means for auto-

matically revolving said gears in one direction only to operate a locking bolt.

2. In combination with a car, a ramp located in the path of said car, a vertical spring pressed rack bar operated by said ramp, gears operated by said bar, and adapted to turn only in one direction and a locking means operated by said gears.

3. In combination with a car, a ramp located in the path of said car, a vertical spring pressed rack bar operated by said ramp, gears operated by said rack bar, a ratchet mechanism for said gears, a pitman operated by said gears, and a pivoted lever connected to said pitman for locking and unlocking a door.

In testimony whereof we affix our signatures.

JOHN VON FRIELING.

HENRY VON FRIELING.
